Inventor
Edward Johnson
Watson E. Coleman
Atty

UNITED STATES PATENT OFFICE.

EDWARD JOHNSON, OF PORT ALLEGANY, PENNSYLVANIA, ASSIGNOR OF ONE-HALF
TO FRED LARSON, OF PORT ALLEGANY, PENNSYLVANIA.

WRENCH.

Application filed April 8, 1924. Serial No. 705,061.

To all whom it may concern:

Be it known that I, EDWARD JOHNSON, a citizen of the United States, residing at Port Allegany, in the county of McKean and State of Pennsylvania, have invented certain new and useful Improvements in Wrenches, of which the following is a specification, reference being had to the accompanying drawings.

10 This invention relates to certain improvements in wrenches and it is an object of the invention to provide a device of this general character with novel and improved means whereby is provided a quick acting 15 sliding adjustment.

Another object of the invention is to provide a novel and improved device of this general character comprising two jaws one movable relative to the other, the movable 20 jaw being provided with means to effect a fine adjustment and also with means whereby the sliding adjustment may be quickly accomplished.

The invention consists in the details of 25 construction and in the combination and arrangement of the several parts of my improved wrench whereby certain important advantages are attained and the device rendered simpler, less expensive and otherwise 30 more convenient and advantageous for use, as will be hereinafter more fully set forth.

The novel features of my invention will hereinafter be definitely claimed.

In order that my invention may be the better understood, I will now proceed to describe the same with reference to the accompanying drawings, wherein:—

Figure 1 is a view in perspective of a wrench constructed in accordance with an 40 embodiment of my invention;

Figure 2 is a view partly in side elevation and partly in section of the device as illustrated in Figure 1;

Figure 3 is a sectional view taken substantially on the line 3—3 of Figure 2;

Figure 4 is a view in perspective of the releasing member as herein disclosed;

Figure 5 is a view in perspective of one of the bearing blocks for the screw;

50 Figure 6 is a view in perspective of the wear blade herein employed.

As disclosed in the accompanying drawings, 1 denotes an elongated shank provided at its outer end with a jaw 2 and along its inner edge with the ratchet teeth 3 with which

is adapted to be engaged the adjusting screw 4. The screw 4 is mounted on a rod 5 the extremities of which being engaged within a block 6. The movable jaw frame 7 is slidably mounted upon the shank 1 and is provided with a transversely disposed opening 8 in which the screw 4 is positioned. The jaw frame 7 above and below the opening 8 is provided with the elongated recesses or pockets 9 circular in cross section and having open the ends thereof opposed to the teeth 3. The block 6 are slidably mounted within the recesses or pockets 9 and the rod 5 is disposed through the entrance slots 11.

The blocks 6 are constantly urged toward the shank 1 to maintain the screw 4 in proper engagement with the teeth 3 through the instrumentality of the resilient members 10, herein disclosed as coil springs, of requisite tension. The sides of the jaw frame 7 above and below the opening 8 are provided with the slots 14 disposed in a direction transversely of the shank 1, said slots 14 being in communication with the pockets or recesses 9.

Disposed through the blocks 6 and extending outwardly through the slots 14 are the rods 15 to provide means whereby the blocks may be moved against the tension of the resilient members or springs 11 to move the screw 4 out of engagement with the teeth 3 so that a quick sliding adjustment of the jaw frame 7 may be effected with respect to the jaw 2. The desired finer adjustment of the jaw frame 7 is accomplished by requisite rotation of the screw 4 when in operative engagement with the teeth 3.

Coacting with the extremities of the rods 15 is a releasing member R. This member R is substantially U-shaped in cross section and bridges the jaw frame 7 from the rear and is provided with the forwardly extending arms 16 extending above and below the opening 8, the rods 15 being operatively engaged with the arms 16 so that normally the intermediate or rear portion 17 of the member R is spaced from the adjacent rear end of the jaw frame 7 but by imposing pressure upon the member R the screw 4 will be moved out of engagement with the teeth 3 when it is desired to effect a quick adjustment of the jaw frame 7.

Surrounding the rod 5 between the upper end of the applied screw 4 and the adjacent upper wall of the opening 8 is a plate or

washer 18 serving to take up thrust imposed upon the screw 4 and having the laterally disposed wings 19 with which contact the inwardly directed lugs 20 provided at the 5 lower marginal portion of the upper arm 16 and at the free end portions thereof. By this means the washer 18 is maintained in effective working position.

As herein disclosed, the opposed faces of 10 the jaw 2 and jaw frame 7 are provided with the removable work engaging plates 21 of a type to permit the wrench herein disclosed to be used with particular advantage as a pipe wrench although I do not wish to be 15 understood as limiting myself in this respect.

From the foregoing description it is thought to be obvious that a wrench constructed in accordance with my invention 20 is particularly well adapted for use by reason of the convenience and facility with which it may be assembled and operated, and it will also be obvious that my invention is susceptible of some change and modification 25 without departing from the principles and spirit thereof and for this reason I do not wish to be understood as limiting myself to the precise arrangement and formation of the several parts herein shown in 30 carrying out my invention in practice except as hereinafter claimed.

I claim:—

1. A wrench of the class described comprising, in combination, a toothed shank 35 provided with a jaw, a jaw frame slidably mounted on the shank and provided with a transverse opening in advance of the shank, said jaw frame above and below the opening being provided with pockets disposed 40 toward the shank, blocks freely mounted in the pockets, means for urging the blocks in a direction toward the shank, the opposed walls of said opening being provided with slots in communication with the pockets, a 45 member extending across the opening and through the slots, said member being engaged with the blocks, a screw mounted on said member to mesh with the teeth of the shank, a release member substantially U-shaped in form bridging the movable jaw frame from the rear and having forwardly 50 extending arms positioned above and below the opening in the movable jaw frame, said movable jaw at opposite sides being provided with slots in communication with the pockets, and rods connecting the blocks and the arms of the release member and extending 55 through the slots in the movable jaw frame.

60 2. A wrench of the class described comprising, in combination, a toothed shank provided with a jaw, a jaw frame slidably mounted on the shank and provided with a transverse opening in advance of the shank, 65 said jaw frame above and below the open-

ing being provided with pockets disposed toward the shank, blocks freely mounted in the pockets, means for urging the blocks in a direction toward the shank, the opposed walls of said opening being provided with 70 slots in communication with the pockets, a member extending across the opening and through the slots, said member being engaged with the blocks, a screw mounted on said member to mesh with the teeth of the 75 shank, a release member substantially U-shaped in form bridging the movable jaw frame from the rear and having forwardly extending arms positioned above and below the opening in the movable jaw frame, 80 said movable jaw at opposite sides being provided with slots in communication with the pockets, rods connecting the blocks and the arms of the release member and extending 85 through the slots in the movable jaw frame, and a thrust plate interposed between one end of the screw and the adjacent wall of the opening in the movable jaw frame, the adjacent arms of the release member being provided with inwardly directed lugs 90 engaging said plate to hold the same in applied position.

3. A wrench of the class described comprising in combination, a toothed shank provided with a jaw, a jaw frame slidably 95 mounted on the shank and provided with a transverse opening in advance of the shank, said jaw frame above and below the opening being provided with pockets disposed toward the shank, blocks freely mounted in 100 the pockets, means for urging the blocks in a direction toward the shank, the opposed walls of said opening extending to a point adjacent said toothed shank and being provided with slots in communication with the 105 pockets, a member extending across the opening and through the slots, said member being disposed through the blocks, a screw mounted on said member to mesh with the teeth of the shank, a release member substantially U-shaped in form bridging the movable jaw frame from the rear and having forwardly extending arms positioned above and below the opening in 110 the movable jaw frame, said movable jaw frame at opposite sides being provided with slots in communication with the pockets, rods connecting the blocks and the arms of the release member and extending through the slots in the movable jaw frame, and a thrust plate interposed between one end of the screw and the adjacent wall of the opening in the movable jaw frame, the adjacent arms of the release member being provided with inwardly directed lugs 115 engaging said plate to hold the same in applied position.

In testimony whereof I hereunto affix my signature.

EDWARD JOHNSON.
